ATTORNEY

UNITED STATES PATENT OFFICE.

FRANK A. FREEMAN, OF PHILADELPHIA, PENNSYLVANIA.

DESIGN FOR A HOSE-SUPPORTER.

SPECIFICATION forming part of Design No. 35,752, dated February 18, 1902.

Application filed October 15, 1901. Serial No. 78,758. Term of patent 14 years.

To all whom it may concern:

Be it known that I, FRANK A. FREEMAN, of the city of Philadelphia, county of Philadelphia, and State of Pennsylvania, have invented and produced a new and original Design for a Hose-Supporter, of which the following is a specification.

In the accompanying drawings, Figure 1 is a front elevation of said hose-supporter, and Fig. 2 is a side view of same.

The leading and characteristic features of my design are the general inverted-pear-shaped configuration, comprising the sides 5 and 6, arcs of the same circle, and the lower 15 semicircular end 7, and the upper horizontally-disposed extension, whose top margin is indicated at 4, which bounds the slot 1 and which joins the pear-shaped configuration in inwardly-extending curves, constituting, approximately, arcs of parabolas.

A further significant feature lies in the opening 2, formed by the sides 5 and 6, which is circular in outline and converges into the very narrow slit 3, extending downwardly to and bounded by the end 7. 25

A further feature of my design comprises the ornamental lip or ridge 8, extending around the edges of opening 2 and slit 3, said lip or ridge extending from one side of the supporter only, as shown in Fig. 2. 30

I claim—

The design for a hose-supporter substantially as herein shown and described.

FRANK A. FREEMAN.
